INVENTOR

Alexander Muirhead.

UNITED STATES PATENT OFFICE.

ALEXANDER MUIRHEAD, OF OAKWOOD, FARQUHAR ROAD, UPPER NORWOOD, LONDON, ENGLAND.

DUPLEX AND MULTIPLEX TELEGRAPH.

SPECIFICATION forming part of Letters Patent No. 230,802, dated August 3, 1880.

Application filed March 24, 1880. (No model.)

To all whom it may concern:

Be it known that I, ALEXANDER MUIRHEAD, a subject of the Queen of Great Britain, doing business at 29 Regency Street, Westmin-
5 ster, England, and resident at Oakwood, Far-
quhar Road, Upper Norwood, London, Eng-
land, have invented certain new and useful
Improvements in Duplex and Multiplex Tele-
graphs, of which the following is a specifica-
10 tion.

The object of my invention is an improve-
ment in the mode or manner of regulating or
adjusting the artificial lines or compensating-
circuits in systems of duplex and multiplex
15 telegraphy, especially those used on aerial and
underground lines.

It consists in introducing in the artificial
line a leakage-circuit of a fixed resistance and
varying its position with regard to the resist-
20 ance of the artificial line.

In all successful systems of multiplex tele-
graphy in which a differential arrangement
of the transmitting and the receiving appa-
ratus is employed there is required for the
25 accurate working of the system a circuit hav-
ing exactly the same electrical resistance and
capacity of the real line. Such circuits are
called "artificial lines" or "compensating-cir-
cuits."

30 Hitherto, in order to compensate further for
the variations of insulation of the real line,
it has been the practice to produce a similar
effect in the artificial-line circuit by varying
both its resistance and capacity, two opera-
35 tions which cause great delay in the working
of the system. In my invention I compen-
sate more quickly for these variations of in-
sulations of the real line by simply inserting
a leakage-circuit in the artificial line and va-
40 rying its position until the resultant insula-
tion-resistance of the artificial line is the
same as the insulation-resistance of the real
line.

The leakage-circuit is of a resistance deter-
45 mined by trials for all to give the best results.
From experience I find five thousand units re-
sistance a very convenient amount to have in
this leakage-circuit.

In the drawings, which represent one mode
50 of carrying out my invention, Figure 1 is a

plan view of a rheostat and adjustable leak-
age-circuit, and Fig 2 a section through the
line 2 2 of Fig. 1.

Rh is a rheostat, consisting of a series of
coils or resistances, r' r^2 r^3 , &c., to r^{10} . These 55
I prefer to make of Muirhead's inductive re-
sistance, as described in United States Let-
ters Patent No. 208,665, of October 1, 1878, to
John Muirhead, Jr., for improvement in con-
densing-resistance, for electric telegraphs. 60

X is the adjustable arm of the rheostat,
pivoted on the axis x, with which it is in elec-
tric communication. Y is another arm work-
ing independently on the axis x, but insulated
therefrom, and also from the arm X. 65

y is the leakage-circuit, made in this in-
stance of ordinary German-silver or platinum-
silver wire, one end of which is attached to
the movable arm Y, and the other to earth.

a a' are contact-points in the resistance-
70 coils r' r^2 r^3 , &c., making contact, respect-
ively, with the arm X of the rheostat and the
arm Y of the leakage-circuit. The arm X is
shown bent and making contact with the outer
75 contact-point a, so as to be completely insu-
lated at all points from the leakage-circuit
and its arm Y.

All variations in the insulation of the real
line can be compensated for by simply vary-
ing the point of application of the leakage-
80 circuit y—that is to say, supposing the resist-
ance of the rheostat to be r^5 , corresponding
to the resistance of the real line, all varia-
tions in the insulation can be compensated for
85 by applying the leakage-circuit at any point
from r' to r^3 . In the drawings the leakage-
circuit is represented as at r^3 .

What I claim as new, and desire to secure
by Letters Patent, is—

1. The hereinbefore-described method of ad-
justing artificial lines or compensating-circuits 90
in systems of duplex and multiplex telegraphy,
which consists in inserting an adjustable leak-
age-circuit in the artificial line and varying its
position, substantially as and for the purpose 95
described.

2. The combination of the artificial line and
the adjustable leakage-circuit, substantially as
described.

3. The combination of the leakage-circuit, 100

consisting of the insulated and adjustable arm and its resistance, with a rheostat consisting of a series of resistances and an adjustable rheostat-arm turning on the same axis as the leakage-circuit, but insulated therefrom, substantially as described.

4. The leakage-circuit consisting of the combination of the insulated and adjustable arm and its resistance, the whole operating substantially as described.

In testimony whereof I have hereunto subscribed my name this 27th day of February, 1880.

ALEXANDER MUIRHEAD.
